UNITED STATES PATENT OFFICE

CARLOS APARICIO Y ELIZALDE, OF ENGRACIA, MADRID, SPAIN

CLOSURE FOR CONTAINERS OR RECEPTACLES FOR MATERIALS IN A LIQUID OR PASTE-LIKE STATE

Application filed November 4, 1930, Serial No. 493,305, and in Spain March 4, 1930.

This invention relates to closures for containers or receptacles for materials in a liquid or paste-like state, and has for an object to provide an improved closure which shall be automatic in use in that pressure exerted by any means whatever on the contents of the container will result in the opening of the closure, through which the contents will flow so long as the pressure is maintained.

10 An automatic closure according to the invention offers the following advantages.

In the use that may be made of the improved closure in connection with tooth-paste tubes and other skin-cream tubes, it presents

15 the following advantages:

1st. It prevents the drying of the paste due to the tube not being closed properly; this operation often being troublesome;

20 2nd. It avoids this trouble, as well as loss of time, soiling of fingers, difficulty of operation, and so forth;

25 3rd. The operation of drawing the paste out of the tube is much easier, a light pressure only need be applied with one hand, leaving the other free to hold the tooth-brush or other medium to which the contents are to be applied.

The closure can also be applied to tubes containing pigments or paints in a pasty state, 30 which, as they harden rapidly on exposure to air, must be kept perfectly enclosed. This end can be attained easily by means of the closure.

According to the present invention, the 35 closing of a container for materials in a liquid or paste-like state is effected by an elastic element which, when at rest, maintains the outlet of the container closed, and which, as a result of pressure exerted on the contents of the container, is forced clear of said outlet to permit the container to be emptied.

40 Preferably, the arrangement is such that upon the release of the pressure on the contents of the container, the elastic element re-assumes its state of rest by virtue of its elasticity, and thus closes the outlet.

In order that the invention may more easily be understood, several closures in accordance therewith are illustrated by the accompanying drawing, by way of example.

In the drawing,

Figure I is a sectional elevation showing the mouth of a container equipped with a closure according to the invention; and

Figure II is a similar view illustrating 55 a modification of the closure shown in Figure I.

Referring now to Figure I in the drawing, *u* is the mouth of a tube or container having mounted thereon a cap *c* provided with an 60 opening *d* in the side wall thereof. The opening *d* is located above the top of the container mouth *u* and provides for ejection of the contents of the container. An elastic valve member *b* in the form of a cup of rubber 65 or similar material having inherent elasticity is located within and substantially fills the cap *c*. A spring *e* presses the rim of the valve member *b* against the wall of the cap *c*, serving to hold the same in place and to prevent material from the container flowing into the cup-shaped valve member. 70

In Figure II the valve member *b* shown in Figure I is replaced by a valve member *a* comprising a closed capsule of rubber or similar material, the capsule *a* fitting snugly within the cap *c*. In this form of the invention, the elasticity of the valve member is derived in part from the air within the same. 75

In either form of the invention, the valve 80 member of the closure normally presses down upon the mouth *u* of the container and effectively seals the same to prevent flow therefrom through the opening *d* in the side wall of the cap *c*. When it is desired to eject material from the container, pressure is applied to the sides thereof, as in the conventional manner of using a tube of paste. The pressure thus applied forces the paste or other plastic or fluid material through the mouth 85 *u* compressing the elastic valve member within the cap *c* and occasioning a flow of material through the opening *d*. When the desired quantity of paste has been ejected, the pressure on the container is relieved, whereupon the inherent elasticity of the valve member causes the same to resume its normal position, closing the mouth *u* and the opening *d*. 90 95

What I claim is:—

1. A device for closing receptacles contain- 100

- ing fluid or plastic material and having an exit opening at one end thereof, which comprises a hollow cap fixedly mounted on said receptacle over said exit opening therein, an opening in the side wall of said cap, and a unitary rubber valve member having compressible side walls and a bottom normally pressing downwardly against said exit opening, said valve member being compressible within said cap to permit the flow of material through said exit opening from said receptacle upon the application of pressure to the said material therewithin, the inherent elasticity of said valve member being sufficient to automatically re-position it against said exit opening and thereby close the same upon relieving the pressure upon the said material.
2. A device for closing receptacles containing fluid or plastic material and having an exit opening at one end thereof, which comprises a hollow cap fixedly mounted on said receptacle over said exit opening therein, an opening in the side wall of said cap, and a unitary rubber valve member comprising a hollow closed capsule having compressible side walls and a bottom normally pressing downwardly against said exit opening, said valve member being compressible within said cap to permit the flow of material through said exit opening from said receptacle upon the application of pressure to the said material therewithin, the inherent elasticity of said valve member being sufficient to automatically re-position it against said exit opening and thereby close the same upon relieving the pressure upon the said material.
